(57) CLAIM

We claim the ornamental design for a bottle, as shown and described.

DESCRIPTION

FIG. 1 is a perspective view of a bottle showing our new design;

FIG. 2 is a front elevational view of the bottle of FIG. 1;

FIG. 3 is a rear elevational view of the bottle of FIG. 1;

FIG. 4 is a left elevational view of the bottle of FIG. 1;

FIG. 5 is a top view of the bottle of FIG. 1 in a larger scale; and,

FIG. 6 is a bottom view of the bottle of FIG. 1 in a larger scale.
